SELECTIVE CONTROL MECHANISM FOR
RADIO SETS

Ransom L. Galinat, Wethersfield, Conn.

Application February 25, 1935, Serial No. 7,967

22 Claims. (Cl. 250—20)

This invention relates generally to means whereby radio sets may be selectively controlled in an automatic manner.

An aim of the invention is to provide an improved and simplified arrangement by means of which radio receiving sets may be automatically dialed or tuned in to receive programs from different transmitting stations at any predetermined or selected time of day and for any predetermined length of time.

A further aim of the invention is to provide an improved arrangement by means of which various stations may be automatically and selectively tuned in, and the volume with which the several programs are reproduced by the set may be selectively and automatically controlled.

A still further aim of the invention is to provide an improved selective station control mechanism wherein the set may be automatically controlled to receive either short or long wave transmissions.

Another object of the invention is to provide an improved arrangement wherein the switches and the electromagnets, through which the station control is effected, are operated on relatively low voltages so as to reduce the cost of operating the set and to reduce likelihood of failure, particularly in burning out of the coils and damage to the switches.

Another object of the invention is to provide an improved selective station control mechanism wherein a more positive and accurate tuning of the receiving set may be had, and disturbances or interferences are minimized.

Another object of the invention is to provide an improved selective station control mechanism of the character described which may be very easily and conveniently adjusted without particular skill or knowledge in order to vary, at will, the transmitting stations from which it is desired to selectively and automatically receive programs.

A still further aim of the invention is to provide an improved selective station control and volume control mechanism which can be incorporated into any of the present day sets without any considerable change in the present design or large additional cost in manufacture; or which can be made as a separate unit for attachment to a set already manufactured.

More particularly, an aim of the invention is to provide certain improvements in the selective control mechanism for radio sets disclosed in the copending application of James H. Denison, deceased, Serial No. 694,980 filed October 2nd, 1933.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings, wherein I have shown, for illustrative purposes, one embodiment which the present invention may take:

Figure 1 is a rear elevational view showing the time mechanism in dotted lines, the selector plate or control dial, and the associated switches;

Fig. 2 is a top plan view of what is shown in Fig. 1;

Fig. 3 is a front view of the clock and associated selector plate;

Fig. 4 is an enlarged view showing the operating means for the tuning shaft;

Fig. 5 is a sectional view taken substantially on line 5—5 of Fig. 4 with parts broken away;

Fig. 5a is a diagrammatic view illustrating the relative positions of the armatures of the several electromagnets;

Fig. 6 is a detail view showing in top plan portions of the levers of the station selector switches and a portion of the lever associated with the short wave switch; and

Fig. 7 is a diagrammatic or schematic layout showing the wiring connections between the various instrumentalities.

Referring to the drawings in detail, A denotes generally a radio set which may be of any suitable sort and, therefore, is shown only in part and more or less diagrammatically in the drawings. The set may have a tuning device of any suitable type, the tuning device in the present instance being shown in Fig. 4 as having the form of a condenser 10 associated with the usual dial shaft 11 carrying a dial 12. The dial shaft may be manually set by the usual knob 13 associated with the dial through a flexible belt 14.

The apparatus may be provided with a clock-driven station selector means such as disclosed in said James H. Denison application. In the accompanying drawings, the clock is designated generally by the letter B. It may be of the electric type (the motor, however, not being shown) and it has the usual train of gears leading to a minute shaft 15. Journaled upon the minute shaft is the usual hour sleeve 16 upon which is mounted for rotation a unit including a sleeve 17, a gear 18, and a selector plate 19. The gear 18 is connected up to the hour sleeve in

such manner that the selector plate is rotated once in twenty-four hours, for example.

The selector plate 19 is provided with a plurality of concentric rows or circles of openings 23a, 23b, and 23c which are adapted to receive plugs or pins 24. The openings in each row may be suitably spaced apart, depending upon the time interval during which it is desirable that the programs be played, in the present instance the spacing being such that there are four openings to each portion of the plate which represents an hour; that is to say, the openings are spaced apart so as to represent time intervals of fifteen minutes each. The selector dial is provided with suitable numerals 25 and associated scale marks 26. The numerals run from one to twelve and represent the twenty-four hours of the day. By preference, one-half of the face of the selector plate is darker than the other half (as represented by shading in the drawings) so as to differentiate the day and night periods. Each circle or row of openings corresponds to a sending station. In the present instance, there are three rows of openings but, obviously, the number of rows may be varied as desired.

Selectively associated with the rows of openings are suitable automatic tuning control switches 30a, 30b, and 30c which are here shown for illustrative purposes as being in the form of mercury switches. Each of these switches comprises a tube including a globule of mercury adapted to close contact between two terminals 31 extending into one end of the tube. Paired with these tuning control switches are set control switches 32a, 32b, and 32c which are also preferably in the form of mercury switches each having a pair of terminals 33. Each pair of switches is carried by a respective rocker or holder 34 pivoted as at 35. Associated with each holder 34 is a lever 36 pivoted, as at 37, and connected at one end to the holder by a spring 38. The arrangement is such that when the left-hand end of a lever is depressed, as shown in Fig. 1, the switches carried by the respective holder are on. When the lever is rocked clockwise, the switches will be thrown into off position with a snap movement because of the spring 38. The several levers 36 are respectively connected by links 39 to operating levers 40a, 40b, and 40c. The pivots for these levers are indicated at 41. The operating levers are respectively associated with the pins or plugs carried by the circles of openings in the selector plate. In the present instance, as will be seen most clearly from Fig. 1, each operating lever has, at its free end, a cam portion 42 against which the pin or pins 24 of the associated row of openings is or are adapted to wipe upon rotation of the selector plate. The selector plate rotates in a counterclockwise direction in Fig. 3 and in a clockwise direction in Fig. 1. The length of each cam portion 42 is substantially such that the stud or plug engaging the same will maintain the associated switches in closed position for a predetermined period of time, in the present instance fifteen minutes. The operating levers 40a, 40b, and 40c are provided with counterweights 43 which normally urge the mercury switches into off positions.

In accordance with the present invention, I provide an improved and novel arrangement of electromagnets through which the tuning control switches effect setting of the tuning means; that is, setting of the dial shaft 11 and the condenser 18 to predetermined relative positions. As hereinafter described more in detail, this im-

proved arrangement permits of operation on relatively low voltages and materially improves the accuracy and nicety with which the tuning is effected. In the present instance, I have shown pairs of electromagnets respectively associated with the tuning control switches 30a, 30b, and 30c, the electromagnets of the several pairs being conveniently designated by the characters 44a, 44b, and 44c. Each of these electromagnets may have a solenoid or coil 45 and an armature 46. The coil may be positioned about a sleeve 47 in which the armature 46 operates. The sleeve may be fixed at its lower end to a base plate 48. The electromagnets of each pair are positioned side by side and preferably to opposite sides of a vertical plane passing through the axis of the shaft 11. The several pairs of magnets are positioned one behind the other; that is, they are spaced apart longitudinally of the shaft. As herein-after described more in detail, the several electromagnets are vertically adjustable in order to set the apparatus to automatically receive programs from various sending stations. In any adjusted position of the electromagnets, the electromagnets of one pair are differentially positioned with respect to the magnets of the other pair. For example, in Fig. 4, I have shown the two central electromagnets 44b as being at the same plane, the electromagnets 44a as in different planes, and the electromagnets 44c in planes reversed with respect to the electromagnets 44a. Fixed to the shaft and preferably having the same angular position thereon are three double armed levers 49 which are respectively associated with the pairs of electromagnets by flexible connections 50 which may be in the form of ball chains. As shown in Fig. 5, the chains 50 are connected to the levers by pivoted links 51, and the lower ends of the chains are adjustably connected to the armatures by means of screws 52. The adjustment is such that when the coils of any pair are energized the armatures of that pair will be drawn down and substantially bottomed against the plates 48 and the chains will be in taut condition.

In order to insure that the programs will be tuned in exactly at the correct time, say at the quarter hour, irrespective of slight inaccuracies in the cam surfaces 42 and the plugs 24, a master switch 54 is provided, and this switch is operated mechanically from the clock mechanism. This switch is preferably in the form of a mercury tube having a pair of terminals 55. The mercury tube is carried by a holder 54' which is connected to a lever 36' by a spring 38'. The lever 36' cooperates with a cam 56 which is driven through suitable gears associated with the clock mechanism so that the cam will make one complete revolution every fifteen minutes, or other selected predetermined time. This master switch is of advantage in that it reduces to a minimum the length of time that the current is on the automatic control mechanism. Thus, it results in a saving of the amount of electricity used and it minimizes noises such as may result from transformer hum or faulty contacts. Also, since it limits the current on the several connections to extremely short periods, failure of the several instrumentalities, such as the switches and transformers, is greatly minimized. The switch thus has a safety factor.

The manner in which the several instrumentalities so far described are electrically connected up will now be briefly stated, particular reference being had to Fig. 7. In this figure, the feed

lines or lead wires are designated by the numerals 66 and 61. The set is connected to these lines in the usual way, and the motor of the clock may be connected across the lines. Manually operable switches 62, 63, and 64 serve the purpose of placing the receiving set under manual or automatic control. The switch 62 is positioned in the line which leads to the set. The switch 63 is included in a wire 65 leading from one of the lines, in the present instance the line 61, to corresponding terminals of the set control switches 32a, 32b, and 32c. The other terminals of these switches are connected by wires 66 to the line 61 between the set and the switch 62. The master switch 54 and the switch 64 are included in a wire 67 leading from the line 60 to the primary coil of a transformer T, the other end of the coil being connected by a wire 68 to the other line 61. The secondary coil of the transformer is connected by wires 69 to one terminal 31 of each of the tuning control switches 30a, 30b, and 30c. The other terminals of these switches are respectively and individually connected to the coils of the several pairs of electromagnets by wires 70a, 70b, and 70c. All of the coils of the electromagnets are connected to the other end of the secondary winding of the transformer by a wire 71. The transformer is of the step-down type so that the tuning control switches and electromagnets will operate on a lower voltage than will the radio set. By way of example, if the radio set operates on 110 volts, the transformer may be such as to step the voltage down to 16 volts, as indicated in Fig. 7.

The operation of the mechanism so far described is briefly as follows: assuming that the outer row of openings 23a of the selector plate represents one station, say WTIC, and it is desired to automatically tune that station in at 12 o'clock midnight, a plug 24 may be inserted, as shown in Fig. 3, in the opening adjacent the numeral 12 which indicates midnight. Assuming that the center circle of openings 23b represents WJZ, and it is desired to bring that station in at 1 o'clock in the morning, a plug 24 will be inserted in the 1 o'clock opening of that circle. Assuming further that the inner row of openings 23c represents station WBR, and it is desired to tune that station in at 1:15 in the morning, a plug 24 will be positioned in the 1:15 opening of that circle. The switch 62 is thrown "off" and the switches 63 and 64 are thrown "on".

Now, when 12 o'clock midnight comes around, the clock will have rotated the selector plate to a position where the 12 o'clock plug engages the cam surface of the lever 40a, whereupon the switches 30a and 32a will be thrown from "off" to "on" positions. When the switch 32a is thrown on, the set is energized. An instant before 12 o'clock, the master switch 54 will be thrown "off" and then almost immediately thrown "on" at exactly 12 o'clock so as to insure that the program is brought in at the exact desired time. When the master switch is "on", a current will flow through the primary of the transformer, and a current will flow momentarily through the secondary of the transformer, switch 30a, wire 70a, electromagnets 44a, and wire 71. When the coils of the electromagnets 44a are energized, the armatures thereof are drawn down so as to set the tuning device at the selected station which, in this instance, is WTIC. The WTIC program will be played for fifteen minutes, and then at 12:15, the plug will ride off the cam surface of the lever 40a whereupon the weight 43 associated with that

lever will cause the mercury switches 32a and 30a to be thrown off. When 1 o'clock arrives, the 1 o'clock plug associated with the circle of openings 23b will engage the lever 40b, thereby throwing the mercury switches 30b and 32b into "on" position. At this time, the master switch will again operate in the manner previously described. The set is now energized through the mercury switch 32b, and the coils of the electromagnets 44b are momentarily energized so as to set the tuning device to station WJZ. The WJZ program will continue for fifteen minutes, and at 1:15 the 1 o'clock plug associated with the central series of openings rides off the cam surface of the lever 40b with the result that the mercury switches 30b and 32b are thrown "off", thus breaking the circuit through the receiving set. As the 1 o'clock plug rides out of engagement with the lever 40b, the 1:15 plug associated with the WBR circle of openings 23c becomes effective so as to tune in station WBR for fifteen minutes. When WBR is tuned in, the set is connected to the lines through the switch 32c, and the coils of the electromagnets 44c are momentarily energized.

It may be stated here that the features of providing electromagnets arranged in pairs and operating the same on relatively low voltage are of considerable importance and advantage in that certain economies in construction and operation are effected, likelihood of failure is reduced, and more accurate and nicer tuning is obtained. In general, these features make for greater reliability and effectiveness. Upon energization of any pair of electromagnets, one of the electromagnets thereof serves to move the tuning shaft and condenser to a predetermined position, and the other electromagnet of that pair serves as a brake, so to speak, the two electromagnets cooperating in such manner as to prevent overthrow of the shaft and to accurately position it and hold it in that position. This may be more readily understood by reference to Fig. 5a wherein the several electromagnets are diagrammatically illustrated with their armatures in those positions which they have when the central pair of electromagnets 44b has been energized. In this case, it will be observed that the two armatures of the electromagnets 44b are practically bottomed against the base plates 48, the chains 50 associated with those armatures are taut, and the arms 49 are horizontal. Assuming now that the electromagnets 44a are energized momentarily, the left-hand armature of that pair is drawn down and bottomed, thereby turning the shaft so that the arms thereon are in the dotted inclined position illustrated in that figure. At the same time that the left-hand armature is drawn down, the right-hand armature is held down by the flux generated within its coil so that, when both armatures are practically bottomed, they are exerting an equal force in opposite directions on the arm 49 and therefore the arm will not be overthrown, but it will be accurately brought to the selected position which will give the best reception for the particular station. The magnets 65 may be operated on a low voltage, thus eliminating the necessity of any automatic throw-off switches in addition to the tuning control switches 30a, 30b, and 30c and the master switch.

In accordance with the present invention and in order that the apparatus may be adjusted so as to automatically tune in programs from any selected transmitting stations, means is provided for adjusting at will the electromagnets of each pair. This adjusting means may take various

forms. In the present instance, I have shown an arrangement wherein the magnets of each pair may be adjusted without requiring adjustment between the several armatures and the arms 48, and without interfering with the operation or affecting the adjustment of the electromagnets of the other pairs. To these ends, each of the base plates 48 may be supported by a respective rod 78 slidably fitting in a sleeve 76 carried by a supporting plate 77. Attached to this plate 77 is a bracket 78 to which are pivoted three levers 79, one for each pair of electromagnets. Each lever is provided with elongated slots 80 in which operate pins 81 projecting laterally from the rods 78. Each lever 79 is pivoted, as at 82, midway between its respective pair of rods 78 so that when the lever is angularly adjusted one of the electromagnets is raised and the other electromagnet is lowered to the same extent that the first one is raised. Associated with each lever is a respective segment 83 having an arcuate slot 84 through which extends a clamping screw 85 carried by the outer end of the lever 79. The face of the segment may bear a scale to indicate the stations or wave lengths, the indicia being omitted in the present instance although the scale marks are illustrated. With this arrangement, when it is desired to adjust any pair of electromagnets (as, for example, if it is desired to adjust the electromagnets 44a so as to automatically bring in station WEAF instead of WTIC) the screw 85 is loosened, the lever 79 is adjusted until the indicating mark on the lever has been brought into registry with the scale mark which indicates WEAF, and then the screw is tightened up to secure the lever in that position. This operation may be very easily carried out by unskilled persons not familiar with the intricacies or theory of radio.

Furthermore, in accordance with the present invention, I provide, in connection with the station selecting means, means of a very simple and effective character for automatically controlling the volume with which the programs sent out from the several stations are reproduced by the radio set. This volume control will now be described, particular reference being had to Figs. 4, 5, and 7. Respectively associated with and operated by the pairs of electromagnets are volume selector switches 86a, 86b, and 86c so arranged that when a given pair of electromagnets has been energized to bring in a certain station, the switch associated therewith is closed while the other two switches are open. Each switch may comprise a circuit closing member 87 the opposite ends of which are connected to the ends of a respective lever 88 by insulating members 89. Each circuit closing member has a pair of contacts 88 which, in the present instance, are adjustable in unison with the electromagnets when the latter are adjusted to change the stations to be automatically received. In the present instance there is secured to each base plate an upright rod 94, and the contacts 88 are carried by the upper ends of these rods in an insulated manner, as illustrated. Each pair of contacts is positioned relative to the contacts of the other pairs in the same manner as the several pairs of electromagnets are relatively positioned. The contacts 88 are preferably in the form of strips of thin resilient metal bent into generally U-shaped form, as illustrated. The manner in which these switches are connected up to the radio set is diagrammatically shown in Fig. 7. The numeral 95 designates the circuit of the radio

set which includes a speaker or transformer and the usual manually operable volume control or rheostat 96 with which sets are ordinarily provided. The contacts 88 at one side may be connected by a common wire 97 to the circuit 95 to one side of the rheostat 96. The contacts 88 at the other side are independently connected by wires 98a, 98b, and 98c to the circuit 95 to the other side of the rheostat 96. Interposed in each of the wires is a respective manually operable volume control or rheostat. These rheostats are respectively designated by the numerals 99a, 99b, and 99c. Interposed in the circuit 95 is a manually operable switch 100 which when "on" places the set under manual control and cuts out the several rheostats 99a, 99b, and 99c. To place the set under automatic volume control, the switch 100 is thrown off, thereby cutting the usual rheostat 96 out of circuit.

In describing the operation of the selective volume control, it will be assumed, for convenience, that the mechanism has been set to bring in stations WTIC, WJZ, and WBR at the times referred to in the description of the operation of the selective station control. The user of the machine, knowing from past experience or by experiment what the setting of rheostat 99a should be for station WTIC, for example, will manually set that rheostat so that the sound output of the radio set when reproducing a WTIC program will be of the desired volume. Likewise, he will set the rheostat 99b to suit the characteristics of station WJZ and rheostat 99c to suit station WBR. When station WTIC is automatically brought in at midnight, the electromagnets 44a move the shaft 11 so that the arms thereof are in the inclined position shown by broken lines in Fig. 5. The circuit closing member 87 of the volume selector switch 86a will close the circuit between the two contacts 88 of that switch so that the rheostat 99a is in the audio circuit. When station WJZ is subsequently brought in, the central pair of electromagnets bring the arms 48 to a horizontal position and the switch 86b is closed, as shown by full lines in Fig. 5. The audio circuit is now through rheostat 99b. When WBR is automatically tuned in, the tuning shaft is brought to a position where the arms thereon are inclined, as indicated by the line x-x of Fig. 5, whereupon the switch 86c is closed and the audio circuit is now through rheostat 99c.

Further, in accordance with the present invention, I provide an improved arrangement whereby the apparatus may be employed to automatically dial or tune in programs from different transmitting stations transmitted either over short or long wave bands. It is usual to provide present day sets with a manually operable switch whereby the set may be tuned into either short or long wave bands. In Fig. 7, I have shown this switch diagrammatically, the same being indicated by the numeral 105. In accordance with the present invention, I provide an arrangement whereby the pins or plugs which selectively control the stations received are also employed to automatically change the set from a long wave receiver to a short wave receiver. Referring to Figs. 1, 2, and 6, 106 designates a lever pivoted as at 107 and having at one end three cams 108 generally similar to the cams on the levers 48a, 48b, and 48c and respectively positioned behind those cams. The several cams 108 are respectively associated with the rows of openings 23a, 23b, and 23c in the selector dial. Connected to

the other end of the lever 108 by means of a link 109 is a pivoted holder 110. Mounted on this holder is a mercury switch 111 which comprises a glass tube provided at one end with a pair of contacts 112 and at its other end with a pair of contacts 113. As shown in Fig. 7, there is fixed to the spindle of the switch 105 a lever 114 the opposite ends of which are connected by chains 115 to armatures within the solenoids 116 and 117. The solenoid 116 is connected in a circuit which includes the secondary winding of the transformer and the contacts 112. The other electromagnet 117 is in a circuit which includes the secondary of the transformer and the contacts 113 of the switch 111.

Now assuming that it is desired to bring in a program from a short wave station, station WBX, for example, at a certain time say 2 o'clock A.M., there is positioned in the 2 A.M. hole of that series which represents station WBX, a stud 240 which is long enough to engage the cam 108 which is associated with that particular set of openings. When 2 o'clock comes around, that pin 240 will engage the associated cams 108 and 42 so that the set will be turned on, the tuning device will be operated in the manner heretofore described, and the wave band switch 105 will be operated so as to change the set into a short wave receiver if the switch 105 has not already been set to that position. More particularly, assuming that the switch 110 is in the position shown in Fig. 1 and the switch 105 is in the long wave position shown in Fig. 7, when the plug 240 operates the lever 108, the switch 110 will be turned to its other position so that the circuit is closed between the terminals 112. The current will then flow through the secondary of the transformer, wire 118, wire 119, terminals 112, and wire 120 which includes the solenoid of the electromagnet 116. This electromagnet is thus energized so that the switch 105 will be moved from the position shown in Fig. 7 to the short wave position. This action is only momentary because of the master switch 54 which is related to the switch 111 in the same manner that it is related to the selector control switches. After the plug 240 rides past the cam 108, the lever 108 will drop back to the position shown in Fig. 1, thereby bringing the switch 111 to the long wave position. The wave band switch 105 will remain in short wave position until the master switch 54 is again closed, whereupon a current will flow through the wire 118, wire 121, terminals 113, and wire 122, which includes the coil of the electromagnet 117. This electromagnet is thus energized whereupon the switch 105 is brought to the long wave position shown in Fig. 7.

As many changes could be made in the above construction and many apparently widely different embodiments of the invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a selective control mechanism for radio sets and in combination with a tuning device of the set, clock mechanism, station selector means

driven by said clock mechanism, a plurality of switches associated with said station selector means and representing the several stations, and a pair of electromagnets for each station respectively associated with each of said switches and arranged to differentially and selectively adjust said tuning device, the electromagnets of each pair being in opposition to each other.

2. In a selective control mechanism for radio sets and in combination with a tuning device of the set, said tuning device having a rotatable member, clock mechanism, station selector means driven by said clock mechanism and having a plurality of control elements representing different stations and adapted to be selectively positioned, a plurality of switches respectively operated by said elements representing the several stations, means automatically maintaining said switches in inoperative positions except when actuated by said elements, a plurality of pairs of electromagnets having movable armatures and having coils respectively associated with said switches so as to be controlled therethrough, said armatures being arranged differentially relative to said rotatable member, and connections between the armatures of said electromagnets and said rotatable member, the electromagnets of each pair being in opposed and balanced relation to one another.

3. In a selective control mechanism for radio sets and in combination with a tuning device of the set having a rotatable member, said tuning device having an angularly adjustable member secured to the rotatable member, clock mechanism, station selector means driven by said clock mechanism and having a plurality of control elements representing different stations and adapted to be selectively positioned, a plurality of switches respectively associated with said elements representing the several stations, a plurality of pairs of electromagnets having coils respectively associated with said switches so as to be controlled therethrough and having armatures respectively connected to said rotatable member, and adjustable connections between said armatures and said adjustable member, the electromagnets of each pair being in opposition to one another and being balanced against one another when energized so as to bring and hold said rotatable member to a predetermined angular position.

4. In a selective control mechanism for radio sets and in combination with a tuning device of the set, said tuning device having a rotatable shaft, clock mechanism, station selector means, a plurality of switches associated therewith, a plurality of pairs of electromagnets having movable armatures and having coils respectively associated with said switches so as to be controlled therethrough, and levers secured to said shaft one for each pair of armatures, said pairs of armatures being respectively connected to said levers in opposed and balanced relation, and said pairs of electromagnets being differentially positioned with respect to said shaft.

5. In a selective control mechanism for radio sets and in combination with a tuning device of the set, clock mechanism, station selector means driven by said clock mechanism, a plurality of switches associated with said station selector means and representing the several stations, a plurality of pairs of electromagnets respectively associated with said switches and arranged to differentially adjust said tuning device, the electromagnets of each pair being in opposition to each other, and means respectively associated

- with each pair of electromagnets for adjustably locating the same in various predetermined positions to change at will the transmitting stations from which it is desired to selectively receive programs.
6. In a selective control mechanism for radio sets and in combination with a tuning device of the set, said tuning device having a rotatable member, clock mechanism, station selector means driven by said clock mechanism and having a plurality of control elements representing different stations and adapted to be selectively positioned, a plurality of switches respectively associated with said elements representing the several stations, a plurality of pairs of electromagnets having armatures and having coils respectively associated with said switches so as to be controlled therethrough, said electromagnets being arranged to differentially adjust said rotatable member, connections between the armatures of said electromagnets and said rotatable member, the electromagnets of each pair being in opposed and balanced relation to one another, and means respectively associated with each pair of electromagnets for relatively prelocating the same in various selective positions with respect to the shaft without disturbing the balanced and opposed relation of the electromagnets.
7. In a selective control mechanism for radio sets and in combination with a tuning device of the set, said tuning device having a rotatable member, clock mechanism, station selector means driven by the clock mechanism, a plurality of switches associated with said station selector means and representing the several stations, a plurality of pairs of electromagnets having armatures having coils respectively associated with said switches so as to be controlled therethrough, means for connecting the armatures of each pair in opposed and balanced relation to said rotatable member, and means for simultaneously adjustably positioning to like extents the electromagnets of each pair with respect to said rotatable member while maintaining the opposed and balanced relation of the electromagnets.
8. In a selective control mechanism for radio sets and in combination with a tuning device of the set, clock mechanism, station selector means driven by said clock mechanism, operative devices including electromagnets differentially positioned between said station selector means and said tuning device and through which said selector means differentially positions said tuning device, a plurality of manually adjustable volume control devices associated with the audio circuit of the set, and separate volume selector switches respectively actuated in unison with each of said operative devices for selectively connecting said volume control devices in the audio circuit of the set.
9. In a selective control mechanism for radio sets and in combination with a tuning device of the set, said tuning device having a rotatable member, clock mechanism, station selector means driven by said clock mechanism and having a plurality of control elements representing different stations and adapted to be selectively positioned, a plurality of switches respectively associated with said elements representing the several stations, a plurality of pairs of electromagnets having armatures and having coils respectively associated with said switches so as to be controlled therethrough, the electromagnets of each pair being positioned side by side and the electromagnets of one pair being differen-
- tially positioned with respect to the other pairs, means for connecting the armatures of each pair of electromagnets in opposed and balanced relation to said rotatable member, and means associated with each pair of electromagnets for adjusting the same with respect to said rotatable member while maintaining the balanced and opposed relation of the electromagnets, said last mentioned means including a lever pivoted between the electromagnets of each pair and connected to the respective electromagnets at like distances from its pivot.
10. In a selective control mechanism for radio sets and in combination with a tuning device of the set, clock mechanism, station selector means driven by said clock mechanism, a plurality of switches associated with said station selector means and representing the several stations, a plurality of pairs of selectively positionable electromagnets respectively associated with said switches and operatively connected to said tuning device so as to move the same differentially to predetermined positions, a plurality of manually adjustable volume control devices associated with the audio circuit of the set, and volume selector means actuated upon energization of said electromagnets for selectively connecting said volume control devices in the audio circuit of the set.
11. In a selective control mechanism for radio sets and in combination with a tuning device of the set, clock mechanism, station selector means driven by said clock mechanism, a plurality of switches associated with said station selector means and representing the several stations, a plurality of pairs of electromagnets respectively associated with said switches and operatively connected to said tuning device so as to move the same differentially to predetermined positions, a plurality of manually adjustable volume control devices associated with the audio circuit of the set, and switch means respectively operated by each pair of said electromagnets when the tuning operation is effected for selectively connecting said volume control devices in the audio circuit of the set.
12. In a selective control mechanism for radio sets and in combination with a tuning device of the set, clock mechanism, station selector means driven by said clock mechanism, a plurality of switches associated with said station selector means and representing the several stations, a plurality of pairs of electromagnets respectively associated with said switches, each pair being operatively connected to said tuning device so as to move the same differentially to a predetermined but adjustable position, a plurality of manually adjustable volume control devices associated with the audio circuit of the set, and a plurality of volume selector switches respectively associated with said pairs of electromagnets and volume control devices for selectively connecting the latter in the audio circuit of the set.
13. In a selective control mechanism for radio sets and in combination with a tuning device of the set, clock mechanism, station selector means driven by said clock mechanism, a plurality of switches associated with said station selector means and representing the several stations, a plurality of pairs of electromagnets respectively associated with said switches and operatively connected to said tuning device so as to move the same differentially to predetermined positions, a plurality of manually adjustable volume control devices associated with the audio circuit of the set.

- of the set, volume selector means respectively actuated by each pair of said electromagnets for selectively connecting said volume control devices in the audio circuit of the set, and means for adjusting said electromagnets and volume selector means.
14. In a selective control mechanism for radio sets and in combination with a tuning device of the set, said tuning device having a rotatable shaft, clock mechanism, station selector means, a plurality of switches associated therewith, a plurality of pairs of electromagnets having armatures and having coils respectively associated with said switches so as to be controlled therethrough, levers secured to said shaft one for each pair of armatures, said pairs of armatures being respectively connected to said levers in opposed and balanced relation and said pairs of electromagnets being differentially positioned with respect to said shaft, a plurality of manually adjustable volume control devices associated with the audio circuit of the set, and a plurality of volume selector switches respectively associated with said levers and respectively connected to said volume control devices.
15. In a selective control mechanism for radio sets and in combination with a tuning device of the set, clock mechanism, station selector means driven by said clock mechanism, a plurality of switches associated with said station selector means representing the several stations, a plurality of pairs of electromagnets, each pair being respectively associated with one of said switches and arranged to differentially adjust said tuning device, the electromagnets of each pair being in opposed and balanced relation to one another, manually operated means respectively associated with each pair of electromagnets for adjustably locating the same at will to change the transmitting stations from which it is desired to selectively receive programs, a plurality of manually adjustable volume control devices associated with the audio circuit of the set, and a plurality of volume selector switches respectively associated with said electromagnets and respectively connected to said volume control devices, said switches being adjustable in unison with said electromagnets.
16. In a selective control mechanism for radio sets and in combination with a tuning device of the set, said tuning device having a rotatable member, clock mechanism, station selector means driven by said clock mechanism and having a plurality of control elements representing different stations and adapted to be selectively positioned, a plurality of switches respectively associated with said elements representing the several stations, a plurality of pairs of electromagnets having armatures and having coils respectively associated with said switches so as to be controlled therethrough, the electromagnets of each pair being positioned side by side and the electromagnets of one pair being differentially positioned with respect to the other pairs, a plurality of levers on said rotatable member, means for connecting the armatures of said pairs of electromagnets to the respective levers in opposed and balanced relation to the rotatable member, means associated with each pair of electromagnets for adjusting the same with respect to said rotatable member while maintaining the balanced and opposed relation of the electromagnets, a plurality of manually adjustable volume control devices associated with the audio circuit
- of the set, and a plurality of volume selector switches respectively associated with said pairs of electromagnets and respectively associated with said volume control devices, each of said last mentioned switches comprising a circuit closing member carried by one of the levers and a pair of contacts carried by and adjustable in unison with said electromagnets.
17. In a selective control mechanism for radio sets and in combination with the tuning device and the wave band switch of the set, clock mechanism, station selector means driven by said clock mechanism and having a plurality of control elements representing different stations and adapted to be selectively positioned, means respectively associated with said elements representing the several stations and through which said tuning device is moved to different predetermined positions, and means controlled by said elements and operatively connected to said wave band switch for moving the latter from one position to another.
18. In a selective control mechanism for radio sets and in combination with the tuning device and wave band switch of the set, clock mechanism, station selector means driven by said clock mechanism and having a plurality of rows of openings, the several rows representing different stations and the openings of each row representing time intervals, control plugs adapted to be selectively positioned in said openings, a plurality of switches respectively associated with the rows of said openings and adapted to be operated by the plugs carried thereby, a plurality of electrically operated operating means for said tuning device and respectively associated with said switches so as to be controlled therethrough and arranged to move said tuning device to different predetermined positions, a switch associated with and common to the several rows of openings and adapted to be operated by the plugs carried thereby, and electromagnet means controlled through said last mentioned switch and operatively connected to said wave band switch for operating the latter.
19. In a selective control mechanism for radio sets and in combination with a tuning device and wave band switch of the set, clock mechanism, dial means driven thereby and having a plurality of circles of openings, control plugs adapted to be selectively positioned in said openings, a plurality of switches respectively associated with said circles of openings, an operative connection between each switch and the control plugs carried by the respective circle of openings, each of said connections including a pivoted lever having a cam surface of a predetermined length representing a predetermined length of time and adapted to be engaged by the respective plug to hold the switch in operated position, a plurality of electromagnets respectively associated with said switches and operatively connected to said tuning device and arranged to move said tuning device differentially to several predetermined positions, an additional switch, a lever through which said additional switch is operated and having a plurality of cams respectively associated with said rows of openings and positioned respectively behind said cam surfaces of said pivoted levers, and electromagnet means controlled by said additional switch and connected to said wave band switch for operating the latter.
20. In a selective control mechanism for radio sets and in combination with a tuning device and

- the wave band switch of the set, clock mechanism, station selector means driven by said clock mechanism and having a plurality of control elements representing different stations and adapted to be selectively positioned, means respectively associated with said elements representing the several stations and through which said tuning device is moved to different predetermined positions, means associated with said last mentioned means for controlling the volume output of the set, and means controlled by said elements and operatively connected to said wave band switch for moving the latter from one position to another.
21. In a selective control mechanism for radio sets and in combination with a tuning device of the set, clock mechanism, station selector means driven by said clock mechanism and having a plurality of rows of openings, the several rows representing different stations and the openings of each row representing time intervals, control plugs adapted to be selectively positioned in said openings, a plurality of pairs of switches respectively associated with the rows of openings and adapted to be operated by the plugs carried thereby, each pair including a set control switch and a tuning control switch, all of said set con-
- trol switches being electrically connected to said set so that when any one thereof is "on", the set is energized, and a plurality of electromagnets for moving said tuning device to different predetermined positions and respectively associated with said tuning control switches so as to be controlled therethrough.
22. In a selective control mechanism for radio sets and in combination with a tuning device of the set, clock mechanism, station selector means driven by said clock mechanism and having a plurality of control elements representing different stations, a plurality of pairs of switches respectively associated with said elements representing the several stations, each pair of switches including a set control switch and a tuning control switch, all of said set control switches being electrically connected to the set so that when any one of said switches is "on" the set is energized, and when all of said switches are "off" the set is out of circuit, and a plurality of pairs of electromagnets respectively associated with said tuning control switches and arranged to differentially adjust said tuning device, said electromagnets of each pair being in opposed and balanced relation to one another.
